UNITED STATES PATENT OFFICE

WALTER M. SCHWARTZ AND FREDERICK KERSHAW, OF PHILADELPHIA, PENNSYLVANIA, ASSIGNORS TO THE PHILADELPHIA TEXTILE MACHINERY COMPANY, OF PHILADELPHIA, PENNSYLVANIA, A CORPORATION OF PENNSYLVANIA.

SCREEN.

1,361,626.

Specification of Letters Patent.

Patented Dec. 7, 1920.

Application filed October 3, 1919. Serial No. 328,194.

To all whom it may concern:

Be it known that we, WALTER M. SCHWARTZ and FREDERICK KERSHAW, citizens of the United States, and residents of Philadelphia, 5 Pennsylvania, have invented certain Improvements in Screens, of which the following is a specification.

Our invention relates to apparatus for drying materials by the circulation of heated 10 air. In such an apparatus the air is laden with light particles of the material being dried.

One object of our invention is to separate the air from the particles by a screen.

15 A further object of the invention is to provide a movable screen, which will carry the particles to one side of the air passage at which point they can be removed from the screen.

20 In the accompanying drawings:

Figure 1 is a side view of one form of drying apparatus illustrating our invention;

Fig. 2 is a sectional view on the line 2—2, Fig. 1;

25 Fig. 3 is an enlarged sectional view through the screen;

Fig. 4 is a detached perspective view of a portion of the screen; and

Fig. 5 is a view illustrating a modification 30 of the invention.

1 is the drying chamber of an ordinary drying apparatus. 2 is the heating chamber, in which are coils of pipe, in the present instance, which heat the air under circula-

35 tion. In the drying chamber there is a series of endless conveyers 3 for carrying material through the drying chamber. In the present instance, there is one conveyer mounted under another and the material drops from

40 one conveyer to the other, first passing in one direction through the chamber and then in the opposite direction. After being carried through the machine by the last conveyer, it is discharged from the apparatus.

45 4, 4 are the circulating fans mounted on shafts 5 adapted to bearings of any suitable type and driven in any suitable manner. These fans circulate the air through the drying chamber and through the heating chamber, as indicated by arrows in Fig. 2.

In drying certain classes of material, small particles of fiber, or other material carried by the circulating air, are deposited on a screen which, heretofore, has been fixed

so as to prevent the material being deposited on the heating pipes, or other heating surfaces. This type of screen is objectionable as the screen becomes clogged by the particles of material and the circulation of air is seriously interfered with. 55

By our invention, we provide means by which a clean surface of the screen can be presented and the clogged portions of the screen can be moved to one side and cleaned. Mounted above the heating chamber and extending over a portion of the drying chamber is a compartment 6, which has an opening 7 communicating with the drying chamber, and is in communication with the heating chamber. 9 is an endless screen band 70 shown clearly in Fig. 4 made, in the present instance, of wire, and having meshes of a given size so that while it will allow the free passage of air, the screen will prevent the passage of a greater portion of the loose 75 material which is carried by the air in circulation. The accumulation of material on the under side of the screen tends to block the passage of air, and, as the screen has a given movement, a clean surface is continuously presented so that the air will at all times be free to circulate through the screen. The small particles of material which adhere to the screen will be carried outside of the drier and will fall off of the screen, 80 or may be removed by a doffer 10, of any suitable type. In the present instance, we have shown a brush which rotates in contact with the screen and removes the particles. The screen, in the present instance, is endless 85 and passes around sheaves 11 and 12 adapted respectively to shafts 13 and 14, one of which is driven.

Communicating with the chamber 6, in the present instance, is a suction pipe 15, 95 in which is a suction fan 16 mounted on a shaft 17 in any suitable manner. On the rotation of the fan a certain quantity of air is removed from the machine and fresh air is admitted at any suitable points.

In Fig. 5, we have shown a reciprocating screen 9^b actuated by a crank 19. At each side of the chamber 6^a is a doffer 10^b, which removes material from the under side of the screen. 100

While, in Figs. 1 and 2, we have illustrated a given type of drier, it will be understood that the invention can be applied to 105

any type of drier. In fact, it can be applied to any machine in which air is in circulation and in which loose particles of material are carried by the air, which it is desirable to separate from the air.

We claim:

1. The combination of a machine in which air is circulated, of a casing having a heating chamber and a drying chamber and a passage connecting the two chambers; a flat screen extending across the inlet of said passage; means for moving said screen; and means, outside of the casing, for removing material from the surface of the screen so that a clean surface is continuously presented to the air passage.
2. The combination of a drier having a drying chamber; a heating chamber; a fan for circulating the air through the drying chamber and the heating chamber; the drier having a passage forming communication between the two chambers through which air in circulation travels; means for carrying the material to be dried in the drying chamber; an endless screen extending over the

passage and forming communication between the drying chamber and the heating chamber; and means for removing material accumulating on the screen, said means being located outside of the casing of the drier.

3. The combination of a drier having a drying chamber and a heating chamber; a fan for circulating air through the chamber; the drier having a passage forming communication between the two chambers independently of the fan passage; means for carrying material through the drying chamber; an endless screen mounted so that one run of the screen will pass over the opening between the drying chamber and the heating chamber; means for moving the screen; means for removing material that accumulates on the screen, said means being located outside of the casing; an exhaust pipe communicating with the space between the two runs of the screen; and an exhaust fan mounted in the pipe so as to draw a certain amount of air from the machine.

WALTER M. SCHWARTZ.
FREDERICK KERSHAW.
